UNITED STATES PATENT OFFICE.

HERMAN T. MENDELSOHN, OF NEW YORK, N. Y., ASSIGNOR TO SIMON & MENDELSOHN, OF NEW YORK, N. Y., A COPARTNERSHIP COMPOSED OF SAMUEL SIMON AND HERMAN T. MENDELSOHN.

DESIGN FOR AN ARTICLE OF MANUFACTURE COMPRISING A FLOUNCING OR EDGING FOR FABRICS.

57,249.

Specification for Design.

Patented Mar. 8, 1921.

Application filed August 20, 1920. Serial No. 404,925. Term of patent 7 years.

To all whom it may concern:

Be it known that I, HERMAN T. MENDELSOHN, a citizen of the United States, and a resident of the city of New York, borough of Manhattan, county and State of New York, United States of America, have invented a new, original, and ornamental Design for an Article of Manufacture Comprising a Flouncing or Edging for Fabrics, of which the following is a specification, reference being had to the accompanying drawing, forming a part thereof.

The figure represents a plan view of my design as adapted to flouncings or edgings for fabrics.

The edging comprises essentially a body portion provided with a grouping of four symmetrically arranged dots disposed at

regular intervals thereon, a series of abutting circles embracing cross-shaped figures, a series of crosses arranged in stepped relationship to each other in conjunction with leaf-like figures, and a serrated border provided with scalloped edges.

The design was primarily intended to be embroidered upon sheer fabrics for use in the manufacture of lingerie, although it is equally adaptable to heavy fabrics for decorative purposes.

What I claim and desire to secure by Letters Patent, is—

The ornamental design for an article of manufacture comprising a flouncing or edging for fabrics substantially as shown and described.

HERMAN T. MENDELSOHN.
